can be caused to collect on the surface of the insulator, and as a result of such an initial coating of dust, the insulator becomes increasingly difficult to clean.

It is an object of the present invention to provide an insulator which will not collect dust on its surface, and which will be easily cleaned.

UNITED STATES PATENT OFFICE

1,941,749

INSULATOR

William A. Hillebrand, Barberton, Ohio, assignor to The Ohio Brass Company, Mansfield, Ohio, a corporation of New Jersey

Application July 29, 1932. Serial No. 626,062

4 Claims. (Cl. 173—318)

This invention relates to electric insulators and particularly to insulators of the suspension type, although it is applicable to insulators of other forms.

One object of the invention is to prevent accumulation of conducting material on the surface of the dielectric members in an insulator string.

Another object of the invention is to provide electric insulators of improved construction and operation.

Other objects and advantages will appear from the following description.

The invention is exemplified by the combination and arrangement of parts shown in the accompanying drawing and described in the following specification, and it is more particularly pointed out in the appended claims.

In the drawing:

Fig. 1 is an elevation with parts in section of two units of a suspension string of insulators.

Fig. 2 is a top plan view of the upper unit shown in Fig. 1.

There are many parts of the world subject to more or less prolonged periods of dry weather. In such localities, insulators used to support electrical transmission lines become coated with dust. It is a matter of experience that this dust coating tends to collect more heavily on those portions 30 of the insulator surface which are subjected to the greatest electrical stress.

The dust from practically all localities when dry is an excellent insulator. However, it generally contains soluble salts which, when the insulator 35 becomes wetted by a fog, dew or light rain, form conducting electrolytes which may reduce the surface resistance of the insulator to a small fraction of one percent of its dry value. This reduction in surface resistance is often so low as to 40 result in flashover at the operating voltage with consequent serious interruption to service.

The two essential elements in this reduction of surface resistance are dust containing soluble salts and moisture. Abundant experience proves 45 that neither one of these alone, even when the moisture is a salt fog, will cause trouble. In some localities an important cause of contamination is soot particles deposited on the insulator surface with the fog itself.

If the dust particles can be kept from depositing 50 on the insulator surface, a large part of the difficulty due to so-called "wet leakage" will be obviated.

The present invention provides an insulator 55 for securing this result, one form of which is illus-

trated in the accompanying drawing. The insulator illustrated is of a cap and pin type having a dielectric member 10 made of porcelain or other vitreous material, a metal cap 11 and a metal pin 12, all similar to the parts of standard insulator units except that the porcelain shell 10 has a smooth under surface at 13, and the cap 11 is provided at its upper peripheral shoulder with an annular ring or flange 14 which is designed to reverse the direction of the electric flux concentration from that which occurs in insulator strings as heretofore used. The flange 14 is provided with an opening or gap as shown in the drawing to permit coupling of the cap with the pin of the next adjacent insulator and to permit moisture 70 to drain from the gutter formed on top of the cap by the flange 14.

In the present conventional type of suspension insulator, the dielectric member is usually provided with downwardly extending petticoats 75 which extend downwardly toward the next lower unit, the cap of which is provided with an extended smooth surface. In view of the fact that porcelain has a specific inductive capacity approximately six times that of air, it is obvious 80 that there will be a concentration of electric flux from the petticoats of the dielectric member to the large smooth surface of the insulator cap below. The flux will be concentrated at the tips of the petticoats but will be spread out over the 85 surface of the cap. It is found that dust accumulation is greatest on those surfaces where the electric field is a maximum and that dust particles carried by the wind across the insulator string are drawn toward the lower porcelain surfaces 90 into those regions where the electric field is a maximum. This causes accumulation of dust on the lower surface of the dielectric member, which action is augmented by eddy currents set up in the pockets between the petticoats. 95

In the present invention as shown in the drawing, the parts are so arranged with respect to one another that the direction of electric field concentration is now reversed, and is a maximum on the cap below and a minimum on the porcelain 100 above. With this arrangement, dust particles which are being carried across the insulator by the wind are drawn downwardly by the concentration of flux produced by the flange 14 toward the metal cap where they can do no harm, instead of being carried upwardly to the porcelain 105 above.

Extensive experiments have also tended to show that ribs or petticoats on the dielectric member of conventional design result in air eddies 110.

which tend to carry dust upward and into the annular grooves in the porcelain, facilitating the deposit of dust upon the porcelain surface. In the present invention, the smooth under surface 5 13 not only prevents concentration of flux on this surface but also avoids the creation of eddy currents and permits the under surface to be swept clean by passing currents of air. In the construction shown in the drawing, any air eddies would 10 be downward toward the metal of the cap below where any deposit of dust can do no harm.

I claim:

1. A suspension insulator comprising a dielectric member having a radially projecting flange, 15 a boss at one side of said flange and a recess in said boss opening at the side of said flange opposite said boss, a cap secured to said boss and a pin secured in said recess, said cap having a peripheral ring at the upper shoulder portion 20 thereof extending upwardly from said cap to form a flux control, tending to concentrate the electrostatic flux in the field about said insulator at the upper extremity of said ring.
2. An insulator string comprising a plurality 25 of units connected in series, each unit comprising a dielectric member having a radially extending flange with a smooth lower surface, a cap secured to said dielectric member at one side thereof and a pin secured to said dielectric member at the opposite side thereof, said cap having 30 a peripheral ring projecting upwardly from the upper shoulder portion of said cap and extending

toward the smooth lower surface of the flange on the next higher insulator in the string to form a flux control for concentrating the flux at the periphery of said ring.

3. An insulator string comprising a plurality of units, each provided with a cap and a pin for securing said units together, said units each having a radially extending flange of dielectric material provided with a smooth lower surface, each cap having an upwardly projecting ring at the upper shoulder portion thereof extending upwardly toward the lower surface of the dielectric flange on the next higher unit in the string, the upwardly projecting ring on each cap having a gap therein to permit moisture to drain from the gutter formed on top of the cap by said ring.

4. An insulator string comprising a plurality of units connected together in series, each unit comprising a dielectric member, a cap and a pin, the dielectric member having a radially extending flange, each of said caps having a peripheral ring extending upwardly from the upper shoulder portion of the cap toward the lower surface of the flange on the next higher unit, the upper extremity of the ring being disposed substantially opposite the lower rim of the cap on the next higher unit so as to concentrate the electrostatic flux between the lower rim of the cap of one unit and the upper portion of the ring of the next lower unit.
